UNITED STATES PATENT OFFICE.

WILLIAM HENRY WILSON, OF NEW BEDFORD, MASSACHUSETTS.

LOOM-SHUTTLE.

1,059,252.

Specification of Letters Patent. Patented Apr. 15, 1913.

Application filed September 25, 1912. Serial No. 722,225.

To all whom it may concern:

Be it known that I, WILLIAM HENRY WILSON, a citizen of the United States, and a resident of New Bedford, in the county of Bristol and State of Massachusetts, have invented a new and Improved Loom-Shuttle, of which the following is a full, clear, and exact description.

The invention relates to self-threading shuttles, such, for instance, as shown and described in the Letters Patent of the United States, No. 987,524, granted to me March 21, 1911.

The object of the present invention is to provide a new and improved loom shuttle arranged to permit of conveniently and securely fastening the thread-retaining device in place in the shuttle body, and to prevent the thread from catching or ballooning.

For the purpose mentioned, use is made of a thread-retaining device formed from a single piece of sheet metal and comprising a base extending transversely in the shuttle body, thread-guide plates rising from the front and rear edges of the said base and having their inner edges overlapping in spaced relation, and a hook extending forwardly from the inner end of the front thread guide plate, the bottom edge of the hook being above the plane of the said base. Use is also made of tongues extending longitudinally from the outer edges of the thread guide plates and engaging longitudinal grooves in the shuttle body, the said tongues terminating in outwardly-bent points embedded in the shuttle body.

A practical embodiment of the invention is represented in the accompanying drawings forming a part of this specification, in which similar characters of reference indicate corresponding parts in all the views.

Figure 1 is a plan view of the delivery end of the improved loom shuttle; Fig. 2 is a sectional plan view of the same; Fig. 3 is a cross section of the same on the line 3-3 of Fig. 2; and Fig. 4 is a perspective view of the thread-retaining device.

The body A of the shuttle is provided with the usual elongated spindle opening B in which extends the spindle C carrying the bobbin D from which unwinds the thread E adapted to pass through a delivery eye F in the side of the shuttle body A. In the top of the shuttle body A adjacent the delivery end is a substantially vertical opening G extending about half way through the shut-

tle body (see Fig. 3) and connected to the recess B by a throat H. The upper end of the opening G and the sides of the throat H are preferably beveled and cut away so as to avoid sharp edges which might cut or sever the thread. The delivery end of the shuttle body is further provided with the usual diagonal slot I extending downwardly in depth to approximately the bottom of the recess G, and a horizontal slot (not shown) connects the lower or innermost portion of the slot I with the transverse delivery eye F. In threading the shuttle the thread E is dropped through the throat H, the recess G, the slot I and its connecting horizontal slot and is then brought into the delivery eye F so that the thread extends out through one side of the latter, as plainly indicated in Figs. 1 and 2. The shuttle so far described is similar to the one referred to in the patent above mentioned.

For preventing a loop in the thread from rising or ballooning out through the slot I, use is made of a thread-retaining device arranged within the recess or opening G, so constructed as to facilitate the entrance of the thread but to prevent its return movement. The thread-retaining device is formed from a single piece of sheet metal bent to provide a base J, from the rear and front edges of which rise thread guide plates J¹, J² having their inner edges overlapping in spaced relation, as plainly indicated in the drawings. The inner end of the thread guide plate J¹ is provided with a forwardly-extending hook J³, the bottom edge of which is secured in a horizontal plane a distance above the plane of the base J so that the thread E can readily pass under the hook J³ to the eye F, and consequently the hook J³ overlies the thread and prevents the same from ballooning upward or catching on the plate J².

In order to securely hold the thread-retaining device in position in the shuttle body A, the following arrangement is made: The outer edges of the thread guide plates J¹ and J² fit in vertical grooves G¹, and from the outer edges of the said plates J¹, J² extend integral, rearwardly-bent parallel tongues J⁴ engaging longitudinal grooves G² formed in the side walls of the recess G and leading to the vertical grooves G¹. The tongues J⁴ terminate in outwardly-bent points J⁵ adapted to be driven into a recess G³ formed in the side walls of the

recess G, as plainly indicated in Fig. 2. Now by the arrangement described the thread guide plates J¹, J² are held against forward or backward movement by engaging the grooves G¹, and the tongues J⁴ fitting into the longitudinal grooves G² prevent tilting of the thread-retaining device, while the points J⁵ engaging the recesses G³ firmly fasten the thread-retaining device in place. It is understood that the tongues J⁴ are sufficiently resilient to permit of readily springing the same and their points J⁵ into place in the grooves G² and the recesses G³ at the time of placing the thread-retaining device in position in the shuttle body A.

The thread-retaining device constructed in the manner described requires no screws, pins or other fastening devices for securely holding the device in position in the body A, and the said thread-retaining device can be readily struck up from a single piece of sheet metal.

Having thus described my invention, I claim as new and desire to secure by Letters Patent:

1. A loom shuttle having a thread-retaining device formed from a single piece of metal and comprising a base extending transversely in the shuttle, thread guide plates rising from the front and rear edges of the said base and having their inner edges overlapping in spaced relation, and a hook extending forwardly from the inner end of the front guide plate, the bottom edge of the hook being above the plane of the said base.

2. A loom shuttle having a thread-retaining device formed from a single piece of metal and comprising a base extending transversely in the shuttle, thread guide plates rising from the front and rear edges of the said base and having their inner edges overlapping in spaced relation, a hook extending forwardly from the inner end of the front guide plate, the bottom edge of the hook being above the plane of the

said base, tongues extending longitudinally from the outer edges of the guide plates, and points extending outwardly from the terminals of the said tongues.

3. A loom shuttle having a body provided with a recess, the side walls of which have vertical grooves and longitudinal grooves leading to the said vertical grooves, and a thread-retaining device in the said recess and made of a single piece of sheet metal, the said device comprising a base resting on the bottom of the said recess, transverse thread guide plates rising vertically from the front and rear edges of the said base and having their inner ends overlapping in spaced relation, the outer ends of the said plates engaging the said vertical grooves, and tongues extending longitudinally from the outer ends of the said plates and engaging the said longitudinal grooves.

4. A loom shuttle having a body provided with a recess, the side walls of which have vertical grooves and longitudinal grooves leading to the said vertical grooves, and a thread-retaining device in the said recess and made of a single piece of sheet metal, the said device comprising a base resting on the bottom of the said recess, transverse thread guide plates rising vertically from the front and rear edges of the said base and having their inner ends overlapping in spaced relation, the outer ends of the said plates engaging the said vertical grooves, tongues extending longitudinally from the outer ends of the said plates and engaging the said longitudinal grooves, and points extending outwardly from the said tongues and embedded in the side walls of the said recess.

In testimony whereof I have signed my name to this specification in the presence of two subscribing witnesses.

WILLIAM HENRY WILSON.
